(57) **CLAIM**

The ornamental design for a confectionery, as shown and described.

DESCRIPTION

The patent or application file contains at least one drawing executed in color. Copies of this patent or patent application publication with color drawing(s) will be provided by the Office upon request and payment of the necessary fee.

1. Confectionery

Figure 1.1 is a front, top and right side perspective view of a confectionery;

Figure 1.2 is a front elevation view thereof;

Figure 1.3 is a back elevation view thereof;

Figure 1.4 is a left side elevation view thereof;

Figure 1.5 is a right side elevation view thereof;

Figure 1.6 is a bottom plan view thereof; and

Figure 1.7 is a top plan view thereof.
